UNITED STATES PATENT OFFICE.

GUSTAF ÖRSTRÖM, OF STOCKHOLM, SWEDEN, ASSIGNEE TO AKTIEBOLAGET GEREH.
ARMEHNS MÄKANISKA VÄRKSTAD, OF STOCKHOLM, SWEDEN, A CORPORATION
OF SWEDEN.

MACHINE FOR PACKING CIGARETTES OR SIMILAR ARTICLES.

Application filed September 14, 1920, Serial No. 410,216. Renewed August 25, 1922. Serial No. 584,341.

To all whom it may concern:

Be it known that I, GUSTAF ÖRSTRÖM, a subject of the King of Sweden, residing at Stockholm, in the Kingdom of Sweden, have invented certain new and useful Improvements in Machines for Packing Cigarettes or Similar Articles, of which the following is a specification.

This invention relates to a machine for packing cigarettes or similar articles in paper-bags, boxes or the like of that class, in which the cigarettes by a suitable mechanism are mounted in a predetermined number in a portioning chamber or chute, from which they are then pushed into the paper-bag or box. According to the invention the machine is provided with a feeler mechanism, which is located at the said portioning chamber and, if the chamber does not contain the predetermined number of cigarettes causes a device to effect a mark in the paper-bag, which has received the incomplete set of cigarettes, so that the said paper-bag may be removed from the other bags, containing the proper number of cigarettes.

In the accompanying drawings Fig. 1 shows in a side view partially in section a cigarette packing machine arranged in accordance with this invention. Fig. 2 is a section on the line 2—2 in Fig. 1. Fig. 3 shows the feeler-mechanism and Figs. 4 and 5 show a marking device in two different positions.

In the drawings the invention is shown applied to a machine of that class, in which the cigarettes 1 are located in a hopper 2 and fed from the same into two vertical channels 3 and 4, separated from one another by a partition wall 5, by two rotating drums 6 and 7 provided in their periphery with grooves 8. From the said drums 6 and 7 the cigarettes are caused to pass into the channels 3 and 4 by suitable guiding members 9, 11 and 12. The partition wall 5 extends downwards into a portioning chamber or chute 22. The bottom 23 of the said chute is carried by a rod 24, the top end of which has a slot for the wall 5. The rod 24 is movable in suitable guides and is engaged by a lever arm 25, fixed to a shaft 26. A second arm 27 is fixed to the shaft 26 and, actuated by a spring or the like, not shown bears against a cam disk 28, provided on a rotating shaft 29. At the top of the chute

22 two knives 30 and 31 are provided, one at 55 each side of the chute. The said knives are carried by arms 32 and 33 respectively, swingably mounted on shafts 34 and 35. Arms 32 and 33 are provided with toothed segments 36 and 37, engaging one another. 60 A spring 38 fixed to the frame of the machine and an arm 39 connected with the arm 33 tends to move the knives 30 and 31 toward one another. An arm 40 is connected with the arm 32 and bears against a cam 65 disk 41 fixed on the shaft 29.

In Fig. 1 a portion of ten cigarettes is located in the chute 22, five on each side of the wall 5, and the knives 30 and 31 are held in their inner position, sustaining the 70 cigarettes located in the channels 3 and 4. The paper-bags, adapted to receive the cigarettes, are located in pockets provided in a drum 42, which is rotated step by step in the direction, indicated by the arrows in 75 Figs. 4 and 5. As one of the said pockets is opposite to the chute 22, the paper-bags 43 contained in the said partition is pushed by an arm or the like not shown upon a nozzle 44, connected with the chute. A plunger 45, actuated in any suitable manner, then pushes the said portion of cigarettes into the paper-bag and returns the latter into the pocket. After the end flaps of the bag has 80 been folded and pasted together, which is 85 effected during the continued rotary motion of the drum 42, the bag is removed from the pocket. These operations may be effected in any suitable manner.

After the cigarettes have been pushed 90 from the chute 22 in the described manner, and the plunger 45 has been returned, the bottom 23 is raised to the knives 30 and 31. The knives 30 and 31 are then withdrawn quickly by the cam disk 41, whereupon the 95 cigarettes contained in the channels 3 and 4 fall down unto the bottom 23. The latter is then lowered slowly by the cam disk 28, so that the chute 22 is again filled with cigarettes. The knives 30 and 31 are then again 100 moved inwards to the position shown in Fig. 1 and the cigarettes contained in the chute are pushed into the subsequent bag.

In order to control, that the chute 22 and each paper-bag contain the proper number 105 of cigarettes, in the present case ten cigarettes, two feelers 46 and 47 according to this invention are provided, one at each

side of the chute. The said feelers are swingably mounted on the shafts 34 and 35 and acted upon by springs 50 and 51, which tend to move the feelers inwards into the chute. Feelers 46 and 47 are provided with arms 52 and 53, adapted to actuate a lever 54, 55 fixed to a shaft 56 and co-operating with a rotating cam disk 57. While the notch 58 of the said cam disk 57 passes by the lever arm 55, the feelers 46 and 47 are permitted to move inwards, acted upon by the springs 50 and 51. If the chute 22 is filled up with cigarettes, the feelers will bear against the uppermost cigarettes in the chute and no motion of the feelers will take place. If, however, one of the compartments of the chute 22 or both the compartments do not contain the proper number of cigarettes, as is the case with the right hand compartment in Fig. 3, the feeler 47 is swung inward by its spring 51, as shown in Fig. 3. Arm 53 of the feeler 47 then forces the lever arm 54 downwards against the action of a spring 72. To the shaft 56 a second arm 59 is fixed, which, consequently, is forced downwards together with the arm 54. The said arm 59 actuates an arm 60 of a catch 61, which is swingably mounted on a pin 62 and by a spring 63, fixed to the frame of the machine, is held in engagement with a projection 64 provided on an arm 65, swingably mounted on a pin 66. Arm 65 has a roller 67, which, by a spring 68, fixed to the arm 65 and the frame of the machine, is forced against a cam surface 69, provided on the drum 42. In Figs. 4 and 5 some pockets of the drum containing bags are shown. At each pocket a notch 70 is provided in the cam surface 69, permitting the arm 65 to be swung inward by the spring 68, provided that the catch 61 previously has been disengaged. The top end of the arm 65 has a cutting edge 71. As the arm 59 is forced downward, as stated above, it disengages the catch 61, so that the arm 65 becomes free and is swung inwards by the spring 68, the cutting edge 71 of the arm 65 being thus brought into the position, shown in Fig. 5, i. e. in the path of the paper-bag 43. The incomplete portion of cigarettes has just before been introduced into the said bag, and while the drum is rotated the edge 71 effects a notch 55 in the bag which consequently easily may be detected and then removed from the bags

leaving the machine. Arm 65 is then removed into the position shown in Fig. 4 by the cam surface 69, and the arm 59 is raised by the cam disk 57, so that the catch 61 engages the projection 64. At the same time the feeler 47 is removed from the chamber 22 by the cam disk 57. If the chute 22 contains the proper number of cigarettes, no feeler will enter the chute and consequently the catch 61 remains in engagement with the arm 65 and the cutting edge 71 of the latter is held out of the path of the bags contained in the pockets of the drum 42.

As the drum 42 and the mechanism rotating the same do not belong to the present invention, they are not more closely described.

I claim:

1. In a machine for packing cigarettes or similar articles in bags, boxes or the like the combination with a portioning chamber, in which the cigarettes are located upon each other, of a feeler adapted to be forced against the uppermost cigarette in the same chamber and to enter the chamber, if incompletely filled, a marking device, and means whereby the said feeler, when entering the chamber, puts into operation the said marking device, so that it effects a mark in the incompletely filled bag.

2. In a machine for packing cigarettes or similar articles in bags, boxes or the like the combination with a portioning chamber, in which the cigarettes are located upon each other, of a feeler adapted to be forced against the uppermost cigarette in the said chamber and to enter the chamber, if incompletely filled, a marking device past which the bags containing cigarettes move, a catching mechanism normally holding the said marking device in inoperative position, a motion transmitting device between the said feeler and catching mechanism, so that the feeler, when entering the portioning chamber disengages the said marking device and the latter effects a mark in the incompletely filled bag, and means for re-engaging the said catching device.

In testimony whereof I have affixed my signature in presence of two witnesses.

GUSTAF ÖRSTRÖM.
